BOTTLE CARRIER CONSTRUCTION FOR BOTTLE WASHERS

George L. N. Meyer, Milwaukee, Wis., assignor to Geo. J. Meyer Manufacturing Co., Cudahy, Wis., a corporation of Wisconsin

Filed May 31, 1961, Ser. No. 113,852
1 Claim. (Cl. 198—131)

This invention relates to an improved bottle carrier for a bottle washing machine.

The improvement of this invention resides in a bottle carrier construction which provides a carrier having increased capacity, i.e. a carrier capable of handling more bottles and/or larger size bottles.

The improved carrier of this invention just as in prior designs includes a top and bottom sheet rigidly secured together by suitable tie strips to form a unitary carrier for mounting on a pair of carrier chains which serve to translate the carriers through a bottle washing machine. The top and bottom sheets are provided with aligned rows of apertures adapted to support and carry a plurality of bottles therein.

The improvement of this invention resides in the construction and arrangement of the strengthening flanges provided at the apertures of the top sheet. Strengthening flanges are located at each of the apertures in the top sheet and add to the structural rigidity of the top sheet and carrier as a whole. It has been found that by making such strengthening flanges at alternate adjacent apertures extend in opposite directions with respect to the plane of the top sheet, the size of the apertures can be increased without impairing the structural strength of the carrier. Thus, by alternating the position of the strengthening flanges the apertures can be increased in size (center-to-center spacing reduced) while still maintaining the required structural rigidity. A carrier of increased capacity results.

Other objects and advantages will be pointed out in, or be apparent from the specification and claim as will obvious modifications of the single embodiment shown in the drawings, in which:

FIG. 1 is a fragmentary plan view of a single bottle carrier embodying the present invention;

FIG. 2 is a sectional view taken along line 2—2 of FIG. 1;

FIG. 3 is a sectional view taken along line 3—3 of FIG. 1; and

FIG. 4 is a sectional view taken along line 4—4 of FIG. 1.

A bottle carrier embodying the present invention is shown in the drawings and identified therein by reference numeral 10. Carrier 10 comprises spaced top and bottom sheets 12 and 14, respectively, securely fastened together by tie strips 16 welded or otherwise secured between flanged edges 18 and 20 at opposite ends of the top and bottom sheets, respectively.

Top and bottom carrier sheets 12 and 14 are preferably made from metal stampings which, when fastened together by tie strips 16, form a unitary bottle carrier 10. A plurality of carriers 10 are mounted between a pair of carrier chains 22 (only one shown) by suitable brackets 24 (only one shown). Carrier chains 22 are provided with a plurality of rollers 26 which ride in a suitable track (not shown) mounted in a bottle washing machine to thereby translate the bottle carriers 10 through

2

the machine by any suitable drive means (not shown).

Top sheet 12 is provided with a plurality of apertures 28 designed to support and steady the bases of bottles 30 (shown in dotted lines in FIG. 3). Bottom sheet 14 is stamped and drawn to provide a plurality of downwardly tapered cup portions 32 having apertures 34 designed to receive and support the necks of bottles 30 which are loaded into the carrier through apertures 28 in the top sheet 12 with the neck of each bottle nested in a cup portion 32 of bottom sheet 14 as shown clearly in FIG. 3.

The top and bottom sheets 12 and 14 are spaced so as to provide support for bottles when in the inverted position shown in FIG. 3 and also to support bottles in a horizontal position when the carriers pass over a supporting wheel in the washer and thereby move in a vertical direction.

To provide a carrier construction capable of handling more bottles and/or larger size bottles the apertures 28 of top sheet 12 are provided with a unique strengthening flange arrangement. As shown clearly in FIG. 2, the top sheet 12 is extruded to form up and down flanges 36 and 38 located at alternate adjacent apertures 28 in the row of apertures extending from one end of a carrier to the other. The ability of the improved construction to handle bottles of increased size and/or reduced center-to-center spacing is clearly shown in FIG. 2 wherein it is seen that the distance between the peripheries of alternate adjacent apertures 28 is equal only to the thickness of the material of flanges 36 and 38. This construction, therefore, provides not only the required structural strength for the carrier top sheet and carrier as a whole but supplies such strength with a minimum of spacing between adjacent apertures. Thus, by using the alternate up and down flanged construction described above it is possible to provide the maximum capacity for the carrier while still maintaining the required structural strength.

Although but one embodiment of the present invention has been illustrated and described, it will be apparent to those skilled in the art that various changes and modifications may be made therein without departing from the spirit of the invention or from the scope of the appended claim.

I claim:

A bottle carrier for a bottle washing machine comprising, a top sheet member, a bottom sheet member spaced from said top sheet member, a plurality of tie strip members rigidly secured to said top and bottom sheet members to fixedly secure said top and bottom sheet members to each other, said top and bottom sheet members each having a row of aligned bottle carrying apertures, said bottle carrying apertures of said top sheet member being provided with integral flanged portions extending at right angles to said top sheet, said flanged portions of alternate adjacent apertures extending in opposite directions with respect to each other with the distance between the peripheries of alternate adjacent apertures being substantially equal to the thickness of the material of said flanges.
